UNITED STATES PATENT OFFICE

152,804

DESIGN FOR A GLASS CANDLE HOLDER OR SIMILAR ARTICLE

Horace King, Newark, Ohio, assignor to A. H. Heisey & Company, Newark, Ohio, a corporation of Ohio

Application June 14, 1947, Serial No. 139,682

Term of patent 14 years

(Cl. D48—2)

To all whom it may concern:

Be it known that I, Horace King, a citizen of the United States of America and a resident of Newark, in the county of Licking and State of Ohio, have invented a new, original, and ornamental Design for a Glass Candle Holder or Similar Article, of which the following is the specification, reference being had to the accompanying drawing, forming a part thereof.

Figure 1 is a perspective view of a glass candle holder or similar article showing my new design.

Figure 2 is a side elevational view of the article shown in Figure 1.

Figure 3 is a vertical sectional view taken along line 3—3 of Figure 4.

Figure 4 is a top plan view of the article shown in Figure 1.

I claim:

The ornamental design for a glass candle holder or similar article, substantially as shown.

HORACE KING.
